UNITED STATES PATENT OFFICE.

FRANK L. UNION, OF NEW YORK, N. Y., ASSIGNOR TO UNION PARTITION COMPANY, OF BOSTON, MASSACHUSETTS, A CORPORATION OF MASSACHUSETTS.

WALL STRUCTURE.

1,199,841.

Specification of Letters Patent.

Patented Oct. 3, 1916.

Application filed November 20, 1914. Serial No. 873,192.

To all whom it may concern:

Be it known that I, FRANK L. UNION, a citizen of the United States of America, residing at New York, borough of Manhattan, county and State of New York, have invented certain new and useful Improvements in Wall Structures, of which the following is a specification.

This invention relates to wall structures, and particularly to such structures wherein plates, slabs, boards such as plaster boards, and sheet metal laths are used.

One of the objects of the invention is to provide a simple and efficient means for constructing such walls.

Another object of the invention is to provide a substantial and efficient wall structure.

These being among the objects of the present invention, others of which will appear hereinafter, the invention consists of certain features of construction to be herein-after described and then claimed with reference to the accompanying drawings illustrating an embodiment of the invention, and in which—

Figure 1 is an elevation of a wall constructed partly in accordance with the present invention showing individual resilient members, except that no outer layer of plaster or finishing material has been applied; Fig. 2 is a similar view, showing the individual resilient members illustrated in Fig. 1 as flexed and put under tension so as to act as flexed and put under tension so as to act 35 to bind the plates, boards or the like in position; Fig. 3 is a transverse section of a wall constructed in accordance with the present invention; Figs. 4 and 5 are detail views showing suitable means for connecting the 40 ends of the individual resilient members to a support; and Figs. 6, 7 and 8 show details.

Referring to the drawings, the floor 10 and the ceiling 11 of a building structure for instance, has a door frame 12 and a window frame 13 for one wall thereof. In this case, preferably struts 14, 15 connect the floor and ceiling and are located just alongside the sides of said frames. These struts are preferably made of channel iron, as 50 shown in cross-section in Fig. 3, with their webs secured next to the frames 12, 13, and their flanges extending away from the same. Thereby grooves such as 16 are provided for the reception of the adjacent ends of the 55 plates, slabs, boards or the like 17, which

constitute a considerable part of the partition or wall. Whether or not the said channel bars are made use of, the said plates, slabs, boards, etc. 17, are supported in position by means of parts which support the 60 same preferably from their opposite faces. To this end there are preferably employed a plurality of individual resilient members such as 18 which are located in substantially the same plane parallel with the wall and 65 are separated a suitable distance apart. Said individual resilient members may consist of bars or rods of steel or iron, with their upper and lower ends suitably and rigidly secured directly to the ceiling and floor, as 70 by the connections illustrated in Figs. 4 and 5. As shown in these views, the ends of the said individual resilient members are provided with eyes 19 through which pass rivets or bolts 20 which also pass through brackets 75 21 suitably secured to the beams such as 22. In Fig. 1, these individual resilient members are shown as substantially parallel, and this is the position which they will be in, in this form of the invention, when they are first 80 connected up at their ends directly to the ceiling and floor to form the eventual wall structure. The said individual resilient members may then be bent or flexed substantially as shown in Fig. 2, so that those of the 85 adjacent pairs are flexed or bent toward each other so as to place them under tension in a direction at substantially right angles to their extent, or they may be obviously flexed in some equivalent way. 90

As shown, the individual resilient members of each pair are flexed toward each other by passing a tie or band 23 of wire or sheet metal around the two members of each pair and twisting the ends of said tie or band 95 together. When the said bands or ties have been sufficiently tightened up, the pairs of individual resilient members will be under considerable tension in the substantial direction of the plane in which the plurality of 100 individual resilient members 18 is arranged. It will be seen that in the embodiment of the invention shown, the individual resilient members 18 of each pair will mutually resist each other, but they will at least be placed 105 under such tension transversely of their extent as to furnish a considerable resistance against the plates, slabs, or boards, etc., 17 which are placed against them, as shown in Fig. 2, no matter what the means for pro- 110

ducing the desired transversely acting tension may be.

Suitable means are provided for supporting the opposite surface of the wall built up of the plates, slabs, boards, etc., 17, and such means may consist of a plurality of similar individual resilient members 24, which are similarly placed under tension in a plane separated from the plane of the first described individual resilient members 18. In such case preferably the individual resilient members at the opposite surfaces of the plates, etc., 17, are paired with each other, that is to say they are opposite to each other. Usually a plurality of individual resilient members, say 18, is first set up and placed under tension, and then the plates, slabs and boards, etc., 17, placed in position to be supported on one side by said individual resilient members 18, and then the support which coacts with the individual resilient members 18 is built in position if it be necessary to use it. Under the present invention the built-up partition is supported or hangs from the ceiling so that little, if any, weight is transmitted to the floor beneath said ceiling. The individual resilient members 18 and 24 may also be connected together, either partly or entirely, as by means of ties or bands 25 which extend transversely of the wall, in which case they preferably extend through the joints between the plates, slabs, boards, etc., 17. To express the matter of these ties 25 differently, they are themselves supported by the members 18 and as they pass through or between the plates or boards 17, they constitute a supporting means for the surface at the other side of the wall opposite said members 18. They do this because they are attached to members, in this case 24, whereby the wall will be supported even though members 24 or the equivalent are not secured at the ends.

It is clear that the wall structure of the present invention may be made either in one plane or in any other cross-section as for instance curved. The invention is well adapted for fireproof walls although it is not limited thereto.

It is obvious that the expansion and contraction of the floor may be compensated for by bending the attached ends of the rods or bars for a short distance, say two inches, at say an angle of 45° to the bodies thereof as shown to the left of Figs. 1 and 2.

Fig. 6 shows how a ground, molding, etc., may be secured in position by the gripping or pinching action of the individual resilient members, as 18. The part or member to be held, such as 27, indicated by dotted lines in Figs. 1 and 2 may have recesses or holes 28 to be engaged by such individual resilient

members. A number of the individual resilient members are shown in Figs. 1, 2 and 7 as composed of two screw-threaded sections to be tightened up, before placing the transverse tension thereon, by means of turn-buckle nuts 29, but this may be desirable only in some cases. In order to secure a plaster-block or the like in position over a frame such as 12, there may be secured to the channel-bar 15, back to back, a short angle bar 30, while to the opposite channel bar 31 there may be secured a short channel bar 32 in similar manner, a detail of which is shown in Fig. 8. It is clear that a part of the proper size may then be fitted and held in position by the bars 30 and 32 as shown in Figs. 1 and 2.

Obviously the present invention is susceptible of modification in other respects, as parts may be omitted, parts added and parts substituted without departing from the breadth of the invention as expressed in the claims.

What I claim as new is:—

1. In a wall structure, the combination with rigid upper and lower supports, of separate, spaced members of lengths of resilient metal, connecting said supports and rigidly attached thereto, said members being arranged in substantially the vertical plane of said wall, a series of disconnected ties subjecting successive pairs of said members to transverse tension and flexing the said members of each of said pairs in opposite directions, and a partition supported by the thus stiffened members in a vertical plane, substantially parallel with the said plane of said members.

2. In a wall structure, the combination of a ceiling and floor, independent rods rigidly and individually connected at the ends with said floor and ceiling, and means for connecting said rods in independent pairs and for placing the said pairs between said ends under transverse tension to stiffen the said pairs of rods and the structure, said ceiling supporting said other parts.

3. In a structure of the class described, the combination of a ceiling and a floor, resilient metallic ties between said ceiling and floor provided with lower ends bent up from the bodies of said ties, whereby the lower end portions comprising said ends are rendered distensible, means for connecting the upper ends of said ties with said ceiling, and means beyond the bends in said lower end portions for connecting said lower ends with said floor, whereby the settling of the floor will distend said end portions.
